UNITED STATES PATENT OFFICE.

JOHN T. HUNTER, OF SUMRALL, MISSISSIPPI.

CHURN-DASHER.

1,388,042.

Specification of Letters Patent. Patented Aug. 16, 1921.

Application filed December 18, 1917. Serial No. 207,687.

To all whom it may concern:

Be it known that I, JOHN T. HUNTER, a citizen of the United States, residing at Sumrall, in the county of Lamar and State 5 of Mississippi, have invented certain new and useful Improvements in Churn-Dashers, of which the following is a specification.

This invention relates to improvements in agitating devices and it is the principal 10 object of the invention to provide a churn dasher which is of such construction as to enable the same to produce a combined vertical reciprocatory rotary motion, thus, materially expediting the churning operation 15 and eliminating considerable time and labor upon part of the user.

It is a more specific object of the invention to provide a churn dasher having the blades thereof formed to cause rotation of 20 the same when the dasher is moved upwardly and downwardly during the usual churning operation.

The improvements in the details and arrangement of parts will be apparent from 25 an inspection of the accompanying drawings, in connection with the specific description hereinafter contained, and wherein the preferred embodiment of the invention is disclosed for the purpose of imparting a 30 full understanding of the same.

In the drawings:—

Figure 1 is a side elevation of the improved dasher, and,

Fig. 2 is a bottom plan of the same.

Having more particular reference to the 35 drawings and in connection with which like reference characters will designate corresponding parts throughout the several views, 1 represents the handle portion of 40 the improved dasher, the lower end of which has the dasher rotatably secured thereto. As will be noted, the dasher includes a body portion 2 having a plurality of radially 45 disposed blades 3 formed thereon. Certain of the sides of the blades 3 are bent downwardly at angles at substantially 45°, thus providing extensions 4, while the remaining sides of the said blades are bent into

vertical positions, thereby providing a plurality of agitating extensions or fins 5. The 50 central portion of the body of the dasher is provided with an opening through which a bearing pintle 6 is passed, the inner end of the said pintle being engaged with the lower end of the handle 1, as hereinbefore 55 stated.

Due to the novel formation of the blades 3, it will be understood that when the handle is moved vertically and the dasher engaged with the milk and cream to be churned, the 60 same will be caused to rotate, since the extensions 4, due to their positioning, will impart rotary movement to the said dasher upon the down stroke of the handle. Consequently, as the dasher rotates the vertical 65 extensions or fins 5 will serve as efficient agitating means movable in substantially horizontal planes while the intermediate or body portions of the blades 3 will serve as efficient agitating means due to the vertical 70 movement of the dasher and handle. In this way, the churning operation will be materially expedited and hence, the labor and time heretofore consumed in such operation 75 will be materially reduced.

It is of course to be understood, that the extensions or fins 4 and 5 may be arranged at varying angles, such as will produce the combined vertical reciprocatory rotary motion of the dasher and therefore, such modifications as are within the scope of my claim, I consider within the spirit of my invention.

I claim:—

A dasher formed of a circular blank made from sheet metal clipped or cut radially and 85 bent to form outwardly tapered arms truncated at their free ends, said ends lying in the plane of the blank, and a downwardly inclined extension at one side edge of each arm and disposed at an angle of approximately 45° relative to the plane of the arm, 90 and a vertical fin inclined toward the center on the other side edge of the arm.

In testimony whereof, I affix my signature hereto.

JOHN T. HUNTER.
